CLAIM

The ornamental design for a sliding locking device for snow chain of dual wheel tire, as shown and described.

DESCRIPTION

FIG. 1 is a perspective view of a sliding locking device for snow chain of dual wheel tire showing my new design;

FIG. 2 is a front side view thereof;

FIG. 3 is a rear side view thereof;

FIG. 4 is a left side view thereof;

FIG. 5 is a right side view thereof;

FIG. 6 is a top plan view thereof;

FIG. 7 is a bottom view thereof; and,

FIG. 8 is a perspective view thereof, wherein the slide and the locking members of the device are separated.

The portions of the photographs in FIGS. 6 and 7 shown in a coarse dot pattern and outlined in dashed lines are included for the purpose of illustrating portions of the sliding locking device for snow chain of dual wheel tire that form no part of the claimed design.

The trademark name “GRIPONE” forming part of the claimed design is a registered trademark of SCS Systems Co. Ltd.
